UNITED STATES PATENT OFFICE.

HAROLD S. OSBORNE, OF NEW YORK, N. Y., ASSIGNOR TO AMERICAN TELEPHONE AND TELEGRAPH COMPANY, A CORPORATION OF NEW YORK.

HIGH-FREQUENCY COMPOSITE SET.

Application filed June 3, 1919. Serial No. 301,433.

To all whom it may concern:

Be it known that I, HAROLD S. OSBORNE, residing at New York, in the county of New York and State of New York, have invented

5 certain Improvements in High-Frequency Composite Sets, of which the following is a specification.

This invention relates to transmission systems in which carrier currents are employed

10 for the transmission of signals.

One of the objects of this invention is to provide a means for separating into different branches of a common transmission circuit frequencies lying to either side of a

15 definite limiting frequency so that low frequency currents may be transmitted over one branch and high frequency currents transmitted over the other.

A further object of the invention has reference to the provision of means whereby a

20 multiplex carrier system may be superposed upon an ordinary signaling line, such as a telegraph or telephone line, without necessitating any alteration or rearrangement of

25 the low frequency apparatus normally associated with such a line.

A still further object of the invention has reference to the provision of means whereby in a system of the character just

30 referred to the carrier frequencies may be separated from the low frequencies, which are ordinarily used in transmitting signals over the line, the carrier frequencies being transmitted over a branch with which are

35 associated a carrier receiving circuit and a carrier transmission circuit so related as to be substantially conjugate with respect to each other; that is, so related that an electro-motive force in the one circuit will be substantially without effect upon the other circuit.

The several objects of this invention are accomplished by connecting a branch to an ordinary transmission circuit, such as a telephone line, at a point where it is desired to separate the carrier frequencies from the ordinary signaling frequencies and including in said branch a broad band filter, so designed as to transmit with negligible attenuation frequencies above the upper range of ordinary signaling frequencies and to substantially suppress frequencies lying below this limit. Such an arrangement will permit the transmission of carrier current over

the branch but will not permit the transmission of the low frequency currents. In order to prevent the high frequency or carrier currents transmitted over the line from passing into that portion of the line beyond the point at which the high frequency

50 branch is connected, another broad band filter is inserted in the line beyond said point, said filter being so designed as to transmit with negligible attenuation frequencies lying below the upper limit of ordinary signaling frequencies and to substantially suppress frequencies above said limit. By means of this arrangement, the carrier frequencies superposed on an ordinary low frequency transmission circuit may

55 be taken off at any desired point and transmitted over a branch to carrier apparatus without any rearrangement of the low frequency circuit.

In order that the branch circuit above referred to, which is used solely for the transmission of carrier currents, may be associated with separate sending and receiving circuits, a balancing transformer and a balancing circuit are provided. In the balancing circuit a filter to balance the filter in the above mentioned carrier branch is provided. The balancing circuit is also provided with two branches, in one of which a low frequency filter for balancing the

60 low frequency filter in the main line is inserted, while the other branch includes a network for balancing the main line.

The invention may now be more fully understood by reference to the following description when read in connection with the accompanying drawing, Figure 1 of which shows in schematic form the general lay out of the terminal carrier equipment superposed upon an ordinary transmission line,

65 such as a telephone or telegraph line, while Figs. 2 and 3 show in detail two arrangements of the high frequency composite set, whereby the carrier system is separated from the ordinary low frequency system.

Referring to Fig. 1, ML represents an ordinary transmission line, such as a telephone line, said line terminating in a terminal line LT, including the usual composite set, whereby the telephone circuit may be composited for Morse operation, and the usual phantom coil Y and composite ringer Z. Since the elements X, Y and Z are well

known in art they are simply indicated schematically upon the drawing and no further description is deemed necessary.

In order that a carrier system may be superposed upon the transmission line **ML**, a carrier branch **CB** is connected to the main line **ML** at the junction point of said main line with the terminal line **TL**, said carrier branch leading to terminal carrier apparatus. In order to prevent the transmission of the carrier frequencies to the terminal line **LT** and the low frequency apparatus associated therewith, a broad band filter **LF** is inserted in the terminal line **LT** said filter being so designed as to transmit frequencies below the upper limit of telephonic transmission and to substantially suppress frequencies above such limit. In order to prevent the transmission of low frequency currents, such as ordinary telephone or Morse currents, to the carrier branch **CB**, a broad band filter **HF** is inserted in said branch, said filter being so designed as to transmit frequencies lying above the upper limit of ordinary telephonic transmission while suppressing frequencies lying below said limit. These filters may be of the general type disclosed in United States patents to George A. Campbell, Numbers 1,227,113 and 1,227,114, dated May 22, 1917. As shown in more detail in Figs. 2 and 3, the high frequency filter **HF** consists of a plurality of sections, each including series capacity and shunt inductance, while the low frequency filter **LF** comprises a plurality of sections, each including series inductance and shunt capacity. The filters, however may be otherwise constructed, the only requirement being that they transmit a band of frequencies having the limits above referred to.

The carrier branch **CB** is associated with a carrier transmitting circuit **TL** and a carrier receiving circuit **RL** to which the various carrier channels are connected. The circuits **TL** and **RL** are associated with the carrier branch **CB** in such a manner as to be conjugate with respect to each other, that is, carrier oscillations transmitted from **TL** to **CB** will be without effect upon **RL** and vice versa. This result is secured by providing a balanced transformer arrangement 10, of well known type, and a balancing circuit **N**.

The details of the balancing circuit **N** are shown in Fig. 2 and comprise a filter **HF'** to balance the filter **HF**, and two branches, one including a network **MN** to balance the main line **ML** and the other including a low frequency filter **LF'** to balance the filter **LF**. If desired the composite set **X** may also be balanced by a network **XN** and the terminal line **LT** may be balanced by a network **TN**. In many cases, however, a sufficient degree of balance may be secured by omitting one or both of the networks **TN** and **XN**.

As illustrated in Fig. 2, the carrier branch

CB is connected to the main line **ML** between said line and the composite set **X**. This connection may, however, be made beyond the composite set as shown in Fig. 3, in which case the corresponding balancing network **XN** will be included in the same branch of the balancing circuit as the network **MN**.

The carrier transmitting and receiving circuits **TL** and **RL** are associated with a plurality of carrier channels, which will now be described. **L₁**, **L₂**, **L₃** and **L₄** represent low frequency telephone or telegraph lines over which telephonic or other signals are transmitted, which signals are to be impressed upon carrier currents and simultaneously transmitted over the main line **ML**. The line **L₁** is associated with a carrier transmitting circuit **TL₁** and a carrier receiving circuit **RL₁** through a balancing transformer arrangement 11 and a balancing network **N₁**, the connection being such that the circuits **TL₁** and **RL₁** will be conjugate with respect to each other. In a similar manner, line **L₂** is associated with circuits **TL₂** and **RL₂** through transformer 12 and network **N₂**; line **L₃** is associated with circuits **TL₃** and **RL₃** through transformer 13 and network **N₃**; and line **L₄** is associated with circuits **TL₄** and **RL₄** through transformer 14 and network **N₄**. Each of the transmitting channels **TL₁**, **TL₂**, **TL₃** and **TL₄** is connected to the common transmitting circuit **TL** while each of the receiving channels **R₁**, **R₂**, **R₃** and **R₄** is associated with the carrier receiving circuit **RL**.

In order to supply the carrier currents having different frequencies for each channel, a frequency control system of the general type disclosed in the application of B. W. Kendall, Serial Number 130,350, filed November 9, 1916, is provided. The frequency control system comprises an oscillator **FG**, which may be of any well known type, such as, for instance, the well known vacuum tube oscillator, said oscillator serving to generate a basic carrier frequency illustrated, by way of example, in the drawing as being 5,000 cycles. In order to translate the basic frequency into harmonics for the different channels, an harmonic producer schematically indicated at **HP** is provided. This harmonic producer may be a vacuum tube arrangement for distorting the waves generated by the oscillator **FG** so as to produce harmonics in the output circuits of the distorting tube. Harmonic producers of this character are shown and described in the above mentioned application of B. W. Kendall, as well as in a patent to B. W. Kendall, No. 1,446,752, dated Feb. 27, 1923. The harmonics produced by the harmonic producer **HP**, which may be for example of 10,000, 15,000, 20,000 and 25,000 cycles, are filtered out and separately transmitted to the

several carrier channels through filtering devices CF_1 , CF_2 , CF_3 and CF_4 . These filtering devices may be broad band filters of the type disclosed in the above mentioned 5 patents of George A. Campbell or may be simple tuned circuits of any well known type. The fundamental frequency here illustrated as 5,000 cycles may be transmitted through a similar filtering arrangement 10 FF to an amplifier FA . The amplifier FA may be of any known type, such as, for instance, a vacuum tube amplifier. The amplified fundamental frequency may be then 15 passed through another filter FF' and impressed upon the transmitting carrier circuit TL . The harmonics used as carrier frequencies after being filtered by means of the filters CF_1 , CF_2 , etc., may be impressed upon carrier amplifiers CA_1 , CA_2 , CA_3 and CA_4 . 20 These amplifiers may be similar to the amplifier FA already referred to.

Each of the transmitting channels TL_1 , TL_2 , etc., is provided with a modulating arrangement schematically illustrated at M_1 , 25 M_2 , M_3 and M_4 . This modulating arrangement may be of any desired character but is preferably a vacuum tube arrangement, such as is illustrated in the patent to B. W. Kendall, No. 1,459,709, dated June 19, 1923, or in 30 the patent to John R. Carson, No. 1,343,307, dated June 15, 1920.

Each of the receiving channels is provided with a demodulator or detector, such as D_1 , D_2 , D_3 and D_4 . These demodulating or detecting arrangements may be of any well known type, but are preferably of the type illustrated and described in the patent of J. R. Carson, Number 1,343,308, dated June 15, 1920. The detecting or demodulating 40 arrangement of the said patent of J. R. Carson employs the so-called homodyne method of detecting, thereby necessitating that the carrier frequency of that particular channel be supplied to the demodulating arrangement. Accordingly, the carrier frequency of 45 each channel after being amplified by the carrier amplifiers CA_1 , CA_2 , etc., is supplied in parallel to the modulating arrangement of the transmitting channel and the demodulating 50 arrangement of the corresponding receiving channel.

The carrier oscillations impressed upon the modulator, as for instance M_1 , are modulated by means of the low frequency signal waves transmitted from the low frequency line, such as line L_1 , to the carrier channel TL_1 , and are then filtered and amplified. For this purpose broad band filters TF_1 , TF_2 , TF_3 and TF_4 are provided in the output 55 circuits of the modulators M_1 , M_2 , M_3 and M_4 . These filters may be of the type disclosed in the patents to Campbell above referred to and each filter should be capable of transmitting a band of frequencies whose 60 width is equal to the range of frequencies 65 employed in low frequency signaling. In the case of telephone transmission, the filter should be so designed as to transmit a band equal to the telephonic range to the exclusion of frequencies lying without this range. 70 The actual frequencies transmitted by the filter of each channel will be different for each channel. The filter of the channel TL_1 transmitting a band of frequencies in the neighborhood of 25,000 cycles, the filter in the next channel transmitting a band in the vicinity of 20,000 cycles, etc. The modulated carrier oscillations transmitted through the filters may be amplified by amplifiers TA_1 , TA_2 , TA_3 and TA_4 arranged in the 75 several transmitting channels. These amplifiers may be of any well known type but are preferably vacuum tube amplifiers. In order to further increase the selectivity, filters TF'_1 , TF'_2 , TF'_3 and TF'_4 may be provided in the output circuits of the amplifiers. 80

The several carrier frequencies are modulated in accordance with the low frequency signals transmitted over the lines L_1 , L_2 , L_3 and L_4 and after being filtered and amplified are 85 simultaneously impressed upon the common carrier transmitting circuit TL , the fundamental frequency here illustrated as being of 5,000 cycles, being at the same time impressed upon the common circuit. These 90 multiple frequencies are then transmitted to the transformer 10 and over the carrier branch CB to the main line ML . Owing to the balancing arrangement of the transformer 10 and the network N , the reaction of 95 these frequencies on the common receiving circuit RL is reduced to small proportions and if a sufficient degree of balance is provided may be rendered negligible. The low 100 frequency filter LF prevents the high frequency carrier oscillations from being transmitted to the terminal line TL .

In each of the receiving channels RL_1 , RL_2 , etc., a broad band filter is inserted on the input side of the demodulating arrangement. These filters are schematically indicated at RF_1 , RF_2 , RF_3 and RF_4 and may be of the same type as the corresponding filters TF_1 or TF'_1 , etc., of the associated 110 transmitting channels. The modulated carrier oscillations transmitted over the main line ML from a distant station pass through the filter HF , being excluded from the terminal line by filter LF , and are then impressed through the transformer 10 upon the common receiving circuit RL . Modulated currents corresponding in frequency to the different channels are filtered out by means of the filters RF_1 , RF_2 , etc., and impressed upon the demodulators D_1 , D_2 , etc. Unmodulated carrier frequencies are at the same time impressed upon the demodulators from the control circuit already described so that the low frequency signal 120 waves, in accordance with which the high 125 width is equal to the range of frequencies 130

frequency carrier waves were modulated, appear in the output circuits of the demodulators.

In order to amplify these low frequency waves, low frequency amplifiers RA_1 , RA_2 , RA_3 and RA_4 are provided in the several receiving channels. These amplifiers may be of any well known type but are preferably vacuum tube amplifiers. In order to purify the low frequency currents from any high frequency components, low frequency filters, such as RF'_1 , RF'_2 , RF'_3 and RF'_4 are provided in the output circuits of the amplifiers. These filters may be of the same character as the low frequency filter LF in the terminal line LT and are of the general type disclosed in the patents to Campbell above referred to. The amplified low frequency signal waves from the several receiving channels are then impressed through the transformers 11, 12, 13 and 14 upon the respective low frequency lines L_1 , L_2 , L_3 and L_4 .

It will be remembered that in connection with the production of the various carrier frequencies, a fundamental frequency of some desired value, such as 5,000 cycles, for example, was generated and transmitted through the filters FF , and FF' and the amplifier FA to the common transmitting circuit TL . This fundamental frequency was then transmitted together with various modulated carrier frequencies through the transformer arrangement 10 and the high frequency filter HF to the main line ML . At a distant point in the main line the various carrier frequencies may be separated from the low frequency signaling currents, such as telephone currents, by means of a high frequency composite set similar to that already described and comprising high frequency and low frequency filters similar to the filters HF and LF . The carrier frequencies may then be impressed upon terminal carrier apparatus similar to that shown in Fig. 1. The terminal carrier apparatus may differ, however, from that shown in Fig. 1 with respect to the production of the carrier frequencies. In order to illustrate the manner in which the system will be modified at the distant station in this respect, the apparatus of Fig. 1 has been shown with a circuit 21 leading from the common receiving circuit RL to a harmonic producer (not shown). The filtering arrangement, such as a tuned circuit FR , is included in the circuit 21 to filter out the fundamental frequency of 5,000 cycles transmitted over the line. This frequency is then impressed by means of the circuit 21 upon an harmonic reproducer which will be in general similar to the harmonic producer HP and the general principle of this arrangement is described in the patent of B. W. Kendall, Number 1,446,752, already referred to. The general arrangement whereby the harmonic reproducer is associated with the receiving circuit is shown and described in the application of B. W. Kendall, Serial Number 130,350, filed November 9, 1916, to which reference has already been made. It is sufficient for the purposes of this application to state that the harmonic reproducer functions to produce harmonics of the basic frequency in a manner similar to the harmonic producer HP already described, the several harmonics being filtered out, amplified to a desired value and then impressed upon the modulating and demodulating apparatus of the terminal system.

The high frequency composite set comprising the present invention is independent of the nature of the terminal carrier apparatus which has been illustrated and described for purposes of illustration and may be used at any point where it is desired to separate the carrier frequencies from the low frequency signal currents which are normally transmitted over the line. This permits of any special treatment which may be desired for either the high frequency carrier currents or the low frequency signal currents at any point along the line and enables the superposition of a carrier system upon an ordinary transmission circuit without any modification of the latter, the entire apparatus being associated with the terminal carrier system so that it can be applied to a line or disconnected therefrom without materially affecting its transmission properties with respect to low frequency currents.

While the invention has been disclosed as embodied in certain circuit arrangements which are deemed to be desirable from a practical standpoint, it will be obvious that the general principles thereof may be embodied in many other organizations widely different from those illustrated without departing from the spirit of the invention as defined in the following claims.

What is claimed is :

1. In a transmission system, a main transmission line adapted to transmit both low frequency currents of an order lower than the upper limiting frequency employed in ordinary telephonic transmission and high frequency currents having frequencies of the order used in carrier transmission, branches leading from said line, one branch being adapted to transmit said low frequency currents and the other branch being adapted to transmit said carrier frequencies, means in the former branch to substantially exclude carrier frequencies while transmitting with substantially uniform attenuation a range of said low frequency currents, and means in the latter branch to substantially exclude said low frequencies while transmitting with sub-

stantially uniform attenuation a range of carrier frequencies.

2. In a transmission system, a main transmission line adapted to transmit both low frequency currents of an order lower than the upper limiting frequency employed in ordinary telephonic transmission and high frequency currents having frequencies of the order used in carrier transmission, branches leading from said line, one branch being adapted to transmit said low frequency currents and the other branch being adapted to transmit said carrier frequencies, a filter in the former branch to substantially exclude carrier frequencies while transmitting with substantially uniform attenuation a range of said low frequency currents, and a broad band filter in the latter branch so arranged and constructed as to transmit with substantially uniform attenuation a range of carrier frequencies and substantially exclude said low frequencies.

3. In a transmission system, a main transmission line adapted to transmit both low frequency currents of an order lower than the upper limiting frequency employed in ordinary telephonic transmission, and high frequency currents having frequencies of the order used in carrier transmission, branches leading from said line, one branch being adapted to transmit said low frequency currents and the other branch being adapted to transmit said carrier frequencies, means in the former branch adapted to substantially suppress currents having frequencies above the upper limits of ordinary telephone transmission while transmitting with substantially uniform attenuation a range of frequencies corresponding to the ordinary telephone range, and means in the latter branch to substantially suppress currents having frequencies below the upper limits of ordinary telephonic transmission while transmitting with substantially uniform attenuation a range of carrier frequencies.

4. In a transmission system, a main transmission line adapted to transmit both low frequency currents of an order lower than the upper limiting frequency employed in ordinary telephonic transmission, and high frequency currents having frequencies of the order used in carrier transmission, branches leading from said line, one branch being adapted to transmit said low frequency currents and the other branch being adapted to transmit said carrier frequencies, a broad band filter in the former branch so constructed and arranged as to transmit with substantially uniform attenuation currents having a range of frequencies below the upper limits of ordinary telephonic transmission and substantially suppress currents having frequencies above said limit, and a broad band filter in the latter branch so constructed and arranged as to transmit with

substantially uniform attenuation currents having a range of frequencies above the upper limits of ordinary telephonic transmission and substantially suppress currents having frequencies below said limit.

70

5. In a transmission system, a telephone line normally adapted to transmit currents of the order used in ordinary telephonic transmission, low frequency terminal apparatus for said line adapted to transmit ordinary telephone currents, and means to superpose a plurality of carrier transmission channels on said line comprising a branch connected to said line between the line and said terminal apparatus, said branch leading to terminal carrier apparatus, means in said branch to substantially suppress the transmission of ordinary telephonic frequency currents thereover while transmitting with substantially uniform attenuation a range of carrier frequencies, and means interposed between said terminal apparatus and the junction point between said branch and the line to substantially prevent the transmission of carrier frequencies to said terminal apparatus while transmitting with substantially uniform attenuation a range of frequencies corresponding to the ordinary telephone range.

80

6. In a transmission system, a telephone line normally adapted to transmit currents of the order used in ordinary telephonic transmission, low frequency terminal apparatus for said line adapted to transmit ordinary telephone currents, and means to superpose a plurality of carrier transmission channels on said line comprising a branch connected to said line between the line and said terminal apparatus, said branch leading to terminal carrier apparatus, a broad band filter in said branch so constructed and arranged as to transmit with substantially uniform attenuation frequencies above the upper limit of ordinary telephonic transmission and substantially suppress frequencies below said limit, and a broad band filter interposed between said terminal apparatus and the junction point of said branch and the line, said filter being so constructed and arranged as to transmit with substantially uniform attenuation frequencies below the upper limit of ordinary telephonic transmission and substantially suppress frequencies above said limit.

90

100

105

110

115

120

125

130

7. In a transmission system, a telephone line normally adapted to transmit currents of the order used in ordinary telephonic transmission, and means to superpose a plurality of carrier transmission channels on a section of said transmission line, said means comprising a branch connected to said line at one end of the section upon which the carrier system is to be superposed, said branch leading to carrier apparatus, means in said branch to substantially suppress the

6
transmission of low frequency currents thereover while transmitting with substantially uniform attenuation a range of carrier frequencies, and means in the line external to the section upon which the carrier system is to be superposed to substantially suppress the transmission of carrier frequencies while transmitting with substantially uniform attenuation a range of frequencies corresponding to the ordinary telephone range.

8. In a transmission system, a telephone line normally adapted to transmit currents of the order used in ordinary telephonic transmission, and means to superpose a plurality of carrier transmission channels on a section of said transmission line, said means comprising a branch connected to said line at one end of the section upon which the carrier system is to be superposed, said branch leading to carrier apparatus, a broad band filter in said branch so constructed and arranged as to transmit with substantially uniform attenuation frequencies above the upper limit of ordinary telephonic transmission and substantially suppress frequencies below said limit, and a broad band filter in the line external to the section upon which the carrier system is superposed, said filter being so constructed and arranged as to transmit with substantially uniform attenuation frequencies below the upper limit of ordinary telephonic transmission and substantially suppress frequencies above said limit.

9. In a transmission system, a main transmission line adapted to transmit both low frequency currents and high frequency currents having frequencies of the order used in carrier transmission, branches leading from said line, one branch being adapted to transmit low frequency currents and the other branch being adapted to transmit carrier frequencies, means in said first mentioned branch to substantially exclude carrier frequencies and means in said second branch to substantially exclude low frequencies, a carrier transmitting circuit and a carrier receiving circuit, means to associate said circuits with said second mentioned branch comprising a transformer and a balancing circuit so arranged that said carrier circuits will be substantially conjugate with respect to each other, said balancing circuit including means to balance said means to exclude low frequency, said balancing circuit also being provided with two branches, one branch including means to balance the means to exclude carrier frequencies from the low frequency branch of the main transmission line, and the other branch including means to balance the main transmission line.

10. In a transmission system, a main transmission line adapted to transmit both low frequency currents and high frequency

currents having frequencies of the order used in carrier transmission, branches leading from said line, one branch being adapted to transmit low frequency currents and the other branch being adapted to transmit carrier frequencies, means in said first mentioned branch to substantially exclude carrier frequencies and a broad band filter in said second branch so arranged and constructed as to transmit carrier frequencies and substantially exclude low frequencies, a carrier transmitting circuit and a carrier receiving circuit, means to associate said circuits with said second mentioned branch comprising a transformer and a balancing circuit so arranged that said carrier circuits will be substantially conjugate with respect to each other, said balancing circuit including means to balance said broad band filter, said balancing circuit also being provided with two branches, one branch including means to balance the means to exclude carrier frequencies from the low frequency branch of the main transmission line, and the other branch including means to balance the main transmission line.

11. In a transmission system, a main transmission line adapted to transmit both low frequency currents and high frequency currents having frequencies of the order used in carrier transmission, branches leading from said line, one branch being adapted to transmit low frequency currents and the other branch being adapted to transmit carrier frequencies, means in the former branch adapted to substantially suppress currents having frequencies above the upper limits of ordinary telephonic transmission, and means in the latter branch to substantially suppress currents having frequencies below the upper limits of ordinary telephonic transmission, a carrier transmitting circuit and a carrier receiving circuit, means to associate said circuit with said second mentioned branch comprising a transformer and a balancing circuit so arranged that said carrier circuits will be substantially conjugate with respect to each other, said balancing circuit including means to balance said means to suppress currents below the upper limits of telephonic transmission, said balancing circuit also being provided with two branches, one branch including means for balancing said means to suppress currents above the upper limits of telephonic transmission, and the other branch including means to balance the main transmission line.

12. In a transmission system, a main transmission line adapted to transmit both low frequency currents and high frequency currents having frequencies of the order used in carrier transmission, branches leading from said line, one branch being adapted to transmit low frequency currents and

- the other branch being adapted to transmit carrier frequencies, a broad band filter in the former branch so constructed and arranged as to transmit currents having frequencies below the upper limits of ordinary telephonic transmission and substantially suppress currents having frequencies above said limit, and a broad band filter in the latter branch so constructed and arranged as to transmit currents having frequencies above the upper limits of ordinary telephonic transmission and substantially suppress currents having frequencies below said limit, a carrier transmitting circuit and a carrier receiving circuit, means to associate said circuits with said second mentioned branch comprising a transformer and a balancing circuit so arranged that said carrier circuits will be substantially conjugate with respect to each other, said balancing circuit including a filter to simulate the characteristics of the broad band filter in said second mentioned branch, said balancing circuit also having two branches, one branch including a filter to simulate the characteristics of said broad band filter in said first mentioned branch of the main line, and the other branch including means to balance said main transmission line.
13. In a transmission system, a main transmission line, branches leading from said line, one branch being adapted to transmit signaling currents of an order below the upper limiting frequency employed in ordinary telephonic transmission and the other branch being adapted to transmit alternating carrier currents upon which signals may be impressed, means in the former branch to substantially exclude carrier frequencies while transmitting with substantially uniform attenuation a range of ordinary frequencies below the upper limiting frequency used in ordinary telephonic transmission, and means in the latter branch to substantially exclude ordinary signaling frequencies while transmitting with substantially uniform attenuation a range of carrier frequencies.
14. In a transmission system, a main transmission line, branches leading from said line, one branch being adapted to transmit signaling currents of an order below the upper limiting frequency employed in ordinary telephonic transmission and the other branch being adapted to transmit alternating carrier currents upon which signals may be impressed, a broad band filter in the former branch to substantially exclude carrier frequencies while transmitting with substantially uniform attenuation a range of ordinary signaling frequencies below the upper limiting frequency employed in ordinary telephonic transmission, and a broad band filter in the latter branch to substantially exclude ordinary signaling frequencies while transmitting with substantially uniform attenuation a range of carrier frequencies below the upper limits of ordinary telephonic transmission and substantially suppress currents having frequencies above said limit, the upper cut-off point of said filter being within the audible range, and a broad band filter in the latter branch so constructed and arranged as to transmit with substantially uniform attenuation currents having a range of frequencies above the upper limits of ordinary telephonic transmission and substantially suppress currents having frequencies below said limit, the lower cut-off point of the latter filter being within the audible limit, thereby permitting the use of carrier frequencies which are not audible.
15. In a transmission system, a main transmission line, a plurality of branches leading from said line, one of said branches being adapted to transmit more currents, another branch being adapted to transmit telephonic currents, and a third branch being adapted to transmit alternating carrier currents upon which signals may be impressed, means in said first mentioned branch to permit the transmission of Morse currents substantially to the exclusion of other currents, means in said second branch to substantially prevent the transmission of currents other than voice currents and means in said third branch to substantially exclude the transmission of currents other than carrier currents.
16. In a transmission system, a main transmission line adapted to transmit both low frequency currents and high frequency currents having frequencies of the order used in carrier transmission, branches leading from said line, one branch being adapted to transmit low frequency currents and the other branch being adapted to transmit carrier frequencies, a broad band filter in the former branch so constructed and arranged as to transmit with substantially uniform attenuation currents having a range of frequencies below the upper limits of ordinary telephonic transmission and substantially suppress currents having frequencies above said limit, the upper cut-off point of said filter being within the audible range, and a broad band filter in the latter branch so constructed and arranged as to transmit with substantially uniform attenuation currents having a range of frequencies above the upper limits of ordinary telephonic transmission and substantially suppress currents having frequencies below said limit, the lower cut-off point of the latter filter being within the audible limit, thereby permitting the use of carrier frequencies which are not audible.
17. In a transmission system, a telephone line normally adapted to transmit currents of the order used in ordinary telephonic transmission, low frequency terminal apparatus for said line and means to superpose a plurality of carrier transmission channels on said line, comprising a branch connected to said line between the line and said terminal apparatus and leading to terminal carrier apparatus, a broad band filter in said branch and arranged so as to transmit with substantially uniform attenuation frequencies above the upper limit of ordinary telephonic transmission and substantially suppress currents having frequencies below said limit, the lower cut-off point of said filter being within the audible limit, and a broad band filter interposed between said terminal apparatus

- and the junction point of said branch and the line, said filter being so arranged as to transmit with substantially uniform attenuation frequencies below the upper limit of ordinary telephonic transmission and substantially suppress frequencies above said limit, the upper cut-off point of the latter filter being within the audible limit.
18. In a transmission system, a telephone line normally adapted to transmit currents of the order used in ordinary telephonic transmission, and means to superpose a plurality of carrier transmission channels on a section of said transmission line, said means comprising a branch connected to said line at one end of the section upon which the carrier system is to be superposed, said branch leading to carrier apparatus, a broad band filter in said branch so constructed and arranged as to transmit with substantially uniform attenuation frequencies above the upper limit of ordinary telephonic transmission and substantially suppress frequencies below said limit, said filter having a lower cut-off point within the audible limit, and a broad band filter in the line external to the section upon which the carrier system is superposed, said filter being so constructed and arranged as to transmit with substantially uniform attenuation frequencies below the upper limit of ordinary telephonic transmission and substantially suppress frequencies above said limit, said last mentioned filter having an upper cut-off point within the audible limit.
19. In a transmission system, a transmission line normally adapted to transmit low frequency currents of an order lower than the upper limiting frequency used in ordinary telephonic transmission, terminal apparatus for said line adapted to transmit said low frequency currents, and means to superpose a plurality of carrier transmission channels on said line, comprising a branch connected to said line between the line and said terminal apparatus and leading to terminal carrier apparatus, means in said branch to substantially suppress the transmission of said low frequency currents thereover while transmitting with substantially uniform attenuation a range of carrier frequencies, said means having a lower cut-off point within the audible limit and means interposed between said terminal apparatus and the junction point between said branch and the line to substantially prevent the transmission of carrier frequencies to said terminal apparatus while transmitting with substantially uniform attenuation a range of signaling frequencies below the limiting frequency used in ordinary telephonic transmission, said last mentioned means having an upper cut-off point within the audible limit.
20. In a transmission system, a transmission line normally adapted to transmit low frequency currents of an order lower than the upper limiting frequency used in ordinary telephonic transmission, and means to superpose a plurality of carrier transmission channels on a section of said transmission line, said means comprising a branch connected to said line at one end of the section upon which the carrier system is to be superposed, said branch leading to carrier apparatus, means in said branch to substantially suppress the transmission of said low frequency currents thereover while transmitting with substantially uniform attenuation a range of carrier frequencies, the lower cut-off point of said means being within the audible limit, and means in the line external to the section upon which the carrier system is to be superposed to substantially suppress the transmission of carrier frequencies while transmitting with substantially uniform attenuation a range of signaling frequencies below the limiting frequency used in ordinary telephonic transmission, said last mentioned means having an upper cut-off at a point within the audible limit.
21. In a transmission system, a main transmission line adapted to transmit both low frequency currents of an order lower than the upper limiting frequency used in ordinary telephonic transmission and currents having frequencies of the order used in carrier transmission, branches leading from said line, one branch being adapted to transmit said low frequency currents and the other branch being adapted to transmit said carrier frequencies some of which may be audible, means in the latter branch to substantially suppress said signaling frequencies of an order lower than the upper limiting frequency used in ordinary telephonic transmission while transmitting carrier frequencies, and a band filter in the former branch having its upper cut-off at a frequency within the audible limit to prevent the transmission to said branch of audible carrier frequencies transmitted over said main transmission line.
22. In a transmission system, a main transmission line adapted to transmit both ordinary telephone currents and currents having frequencies of the order used in carrier transmission, branches leading from said line, one branch being adapted to transmit ordinary telephone currents and the other branch being adapted to transmit carrier frequencies some of which may be audible, means in the latter branch to substantially exclude ordinary telephone currents while transmitting said carrier frequencies, and a band filter in the former branch having its upper cut-off point at a frequency above the highest frequency used in ordinary telephonic transmission but within the audi-

ble range to prevent the transmission to said branch of audible carrier frequencies transmitted over said main line.

23. In a transmission system, a main transmission line, branches leading from said line, one branch being adapted to transmit low frequency signaling currents of an order lower than the upper limiting frequency used in ordinary telephonic transmission and the other branch being adapted to transmit alternating carrier currents some of which may be audible, means in the former branch to substantially exclude said carrier frequencies while transmitting with substantially uniform attenuation a range of signaling frequencies of an order lower than the upper limiting frequency used in ordinary telephonic transmission, said means having an upper cut-off point within the audible range to exclude audible carrier frequencies, and means in the latter branch to substantially exclude signaling frequencies of an order lower than the upper limiting frequency used in ordinary telephonic transmission while transmitting with substantially uniform attenuation a range of carrier frequencies, said last mentioned means having a lower cut-off point within the audible limit to permit the transmission of audible carrier currents above said limit.

24. In a transmission system, a main trans-

mission line, branches leading from said line, one branch being adapted to transmit low frequency signaling currents of an order lower than the upper limiting frequency 35 used in ordinary telephonic transmission and the other branch being adapted to transmit alternating carrier currents some of which may be audible, a broad band filter in the former branch to substantially exclude said 40 carrier frequencies while transmitting with substantially uniform attenuation a range of signaling frequencies of an order lower than the upper limiting frequency used in ordinary telephonic transmission, said filter having an upper cut-off point within the audible limit to exclude audible carrier frequencies, and a broad band filter in the latter branch to substantially exclude signaling 45 frequencies of an order lower than the upper limiting frequency used in ordinary telephonic transmission while transmitting with substantially uniform attenuation a range of carrier frequencies, said last mentioned filter having a lower cut-off point within the audible limit to permit the transmission of audible 50 carrier currents above said limit.

In testimony whereof, I have signed my name to this specification this second day of June, 1919.

HAROLD S. OSBORNE.
